Application filed December 10, 1879. Term of patent 3½ years.

To all whom it may concern:

Be it known that I, FRANK H. SHEPHERD, of Boston, in the county of Suffolk and State of Massachusetts, have invented and produced

5 a new and original Design for a Holder for Flowers, Matches, &c., of which the following is a full, clear, and exact description, reference being had to the accompanying photograph, making part of this specification.

10 This invention consists in a design for a holder for flowers, matches, &c., to be used as an ornament for tables, mantel-pieces, &c.

In the photograph, A is a base, representing the ground, from which rises a pump, B, 15 alongside of which is placed a trough, C, which forms a receptacle for holding flowers,

matches, &c., a beautiful and unique design being thus produced.

Witness my hand this 6th day of December, A. D. 1879. 25
